D. W. DAUGHETEE

PROTECTING SHIELD FOR COOKING STOVE BURNERS

Filed Sept. 27, 1922

Inventor
D. W. Daughhetee

By *Alfred J. Randolph Jr.* Attorney

UNITED STATES PATENT OFFICE.

DAN W. DAUGHETEE, OF KIOWA, KANSAS.

PROTECTING SHIELD FOR COOKING-STOVE BURNERS.

Application filed September 27, 1922. Serial No. 590,870.

To all whom it may concern:

Be it known that I, DAN W. DAUGHETEE, a citizen of the United States, residing at Kiowa, in the county of Barber and State 5 of Kansas, have invented certain new and useful Improvements in Protecting Shields for Cooking-Stove Burners; and I do hereby declare the following to be a full, clear, and exact description of the invention, such 10 as will enable others skilled in the art to which it appertains to make and use the same.

This invention relates to a protective shield for cook stove burners and it aims to 15 provide a novel means whereby material falling from or boiling over from cooking vessels will be passed or deflected away from the burner so as not to extinguish the flames and in the case of oil stoves, not saturate 20 and injure the wick thereof.

It is particularly aimed to provide a construction which will form an attachment for the grid of such a stove involving securing means to attach it to the grid and a collar 25 extending from the shield and into the grid opening.

Additional objects and advantages will 30 become apparent from a consideration of the description following taken in connection with accompanying drawings illustrating one practical embodiment.

In said drawings:—

Figure 1 is a fragmentary vertical sectional view through an oil cook stove showing my improvements in place; 35

Figure 2 is a plan view through the attachment alone, and

Figure 3 is a diametric sectional view on an enlarged scale and on the line 3—3 of 40 Figure 2 showing the attachment of the shield to the stove grid.

Like reference characters designate like or similar parts in the different views.

Referring specifically to the drawings, an 45 oil cook stove is generally suggested at A having a casing B in which an oil burner C is disposed below a top E removably supported over the burner and on the top E. Said grid of course may be of any suitable construction usually having an inner ring 10, an outer ring 11, and diametric bars 12 integral with the rings 10 and 11 and extending outwardly beyond the ring 11 so

as to directly engage the top E for support on said top. In accordance with the invention, an annular inclined deflector or fender 12' essentially comprises the attachment, which is open at its center and there surrounded by a collar 13 fastened as by a bolt 13^a to a flange 13^b of the fender. Collar 13 55 is preferably perforated as shown so that the flame or heat may spread therethrough. The grid has a central opening into which said collar 13 extends, in view of the fact that the bars 12 terminate short of the center 60 of the grid.

The attachment is adapted to be supported directly from the grid and removably. To this end stove bolts 14 or the equivalent may be passed through openings 70 15 in the ring 10 and openings 16 in the flange 12'. Nuts 15^a are provided on said stove bolts. The flange 12' is properly spaced from the top by sleeves or tubes 16.

It will be noted that the diameter of the 75 opening surrounded by flange 13 is less than the diameter of burner C and its wick.

As a result of the construction described, the attachment may be readily secured to a 80 grid of usual construction by means of the stove bolts 14 and associated parts.

It will be realized that in use, the grid supports cooking utensils as usual and that in the event the contents thereof should boil over the same would be deflected by the 85 flange 12' away from the burner C so that it could not engage the same in order to extinguish the flame, and particularly in the case of an oil stove,—engage the wick and ruin it as well as extinguish the flame. 90

As merely one practical embodiment has been illustrated and described, it is to be understood that changes in the details may be resorted to provided they fall within the spirit and scope of the invention. 95

I claim as my invention:—

1. In combination with a stove having an apertured top, a burner and a grid thereover, a protective shield for the burner, said shield consisting of an endless inclined 100 flange, a collar rising from said flange, said collar being perforated and substantially fitting and disposed within said opening, and fastenings passing through said grid and said flange. 105

2. In combination with a stove having an

apertured top, a burner and a grid thereover having an opening therethrough, a protective shield for the burner consisting of an endless inclined flange, a collar occupying and substantially fitting said opening, said collar being perforated, said flange having an upstanding portion disposed within the collar, bolts passing through said grid and

10 said flange, and spacing sleeves on said bolts intermediate said grid and said flange.

In testimony whereof I affix my signature in presence of two witnesses.

DAN W. DAUGHETEE.

Witnesses:

E. I. LONG,

W. M. BOTKIN.
